UNITED STATES PATENT OFFICE

2,663,956

GARMENT PRESS WITH A SINGLE
MANUAL CONTROLJohn Simpson, Jr., and George O'Dell, Luton,
England; said O'Dell assignor to John Simpson,
Luton, England

Application February 11, 1948, Serial No. 7,628

11 Claims. (Cl. 38—30)

1

This invention concerns improvements relating to garment and like presses, such as are used for hot-pressing in laundries, of the kind comprising pressing means and a horizontally rotatable carrier with two tables which can be brought in turn into the pressing position. Usually the pressing means comprise a fixed press head and a vertically movable ram by which the table in position is raised to press an article against the head, the tables and head being steam heated. Generally the ram is operated by fluid pressure, whereas the table-carrier is turned by hand. However, it has already been proposed that the carrier should be turned by fluid pressure.

According to one such proposal, the carrier was to be turned first in one direction and then in the other, separate control devices being provided for the two directions of rotation. According to another proposal, the press, once set in operation by a control device, was to continue to operate automatically, the carrier continuing to turn intermittently in the same direction until the press was set out of operation. The carrier was turned through a unidirectional clutch device permitting idle return movement of the pressure-operated driving means.

It is an object of the invention to provide a simple but reliable machine of the kind set forth in which, in particular, complex control arrangements and reliance upon spring action for the principal operations are avoided.

According to the present invention, the carrier is arranged to be turned positively by fluid-pressure operated means always in the same direction of rotation and the cycle of each individual pressing operation is arranged to be separately initiated and automatically completed in response to a single action by the operator, such action consisting in the same operation of a single control device for each cycle. With the usual pressing means referred to above, this cycle consists in the withdrawal of the ram to lower the one table away from the head, the turning of the carrier through 180° to move that table to a position accessible to the operator and the other table to a position between the head and ram, and finally the elevation by the ram of the said other table for pressing an article. In the course of the next cycle, the carrier is again turned through 180° in the same direction.

Apart from being simple to operate, the press in accordance with the invention can be made readily accessible.

A preferred embodiment of the invention will now be described by way of example and with

2

reference to the accompanying drawings, in which:

Fig. 1 is a side elevation, partly in section, of a garment press.

Fig. 2 a plan view, to a larger scale and partly in section, of a portion of the said press.

Fig. 3 a similar elevational view of a portion of the press as seen from the side opposite to Fig. 1.

Fig. 4 a section through the means for turning the carrier of the press, and

Fig. 5 a detail elevational view of a cut-off valve and its operating means.

Fig. 6 is a schematic view of the more important parts of the machine illustrating the functional inter-relation of the parts without regard to their exact location and construction.

Structurally, the machine illustrated consists of a base, press head and rotary table carrier:

20 A box shaped base 1 (Fig. 1) houses a cylinder 2 for a piston 3 connected to a vertical ram 4 whose upper end projects through a cylinder cover 5 above the base. The head 6, which is of the known flat oblong shape and is provided with means (not shown) for the circulation of heating steam, is supported horizontally some distance above the ram 4 by two columns 7 of goose-neck shape which extend upwardly and slightly outwardly from one end of the base and have their ends turned inwardly over the head.

25 Two oblong tables or bucks 8, each with the usual railed platform 9 underneath it, are supported above the ends of opposed radial arms 10 of the carrier 11, the tables extending at right angles to the said arms. To permit of vertical movement of the tables 8, they are mounted upon plungers 12 which extend below the platforms 9 and are slidably guided in sleeves 13 formed at the ends of the arms 10. Auxiliary guided plungers 14 may serve to steady the tables. The arms 10 project from a hub member 15 supported upon a tubular spindle (not shown) which is rotatably mounted in roller bearings in a bracket 16 projecting from the end of the base 1 remote from the columns 7. The bearing structure comprises a steam inlet and exhaust system connected by flexible tubes 17 to heating circuits in the tables 8.

30 Connected to the carrier hub 15 is an externally toothed ring 18 (Figs. 2 and 3) engaged by a toothed wheel 19 which is carried by a sleeve 20 (Fig. 4) in a bearing 21 supported by an extension 22 of the bracket 16. The lower end of the sleeve 20 is formed with the female portion 45 of a dog clutch with a positive coupling action,

35

40

45

50

55

Connected to the carrier hub 15 is an externally toothed ring 18 (Figs. 2 and 3) engaged by a toothed wheel 19 which is carried by a sleeve 20 (Fig. 4) in a bearing 21 supported by an extension 22 of the bracket 16. The lower end of the sleeve 20 is formed with the female portion 55 of a dog clutch with a positive coupling action,

as shown a single diametrical slot 23. The male portion of the clutch, comprising complementary dogs 24, is formed on the upper side of a flange 25 of a cylindrical member 26 which is slidable axially in the sleeve 20 against the resistance of a compression spring 27 abutting against the wheel 19. The member 26 rests by way of a ball 28 and follower pin 29 upon the edge of a cam 30 which is fast upon a shaft 31, the throw of the cam being sufficient for producing engagement and permitting disengagement of the dog clutch 23, 24. Fixed upon the member 26 below the flange 25 is a pinion 32 which meshes with a rack 33 formed on one side face of a driving plunger 34 working in a cylinder 35, the pinion 32 projecting through a slot 37 (Fig. 2) in the cylinder wall for that purpose. The rack teeth are made sufficiently long to maintain engagement in spite of the vertical movement of the sleeve 26 and pinion 32. The plunger 34 is furnished with a piston packing 38 and the cylinder 35 with an inlet and exhaust connection 39 for pressure fluid, in this case compressed air. There may also be adjustable abutment means (not shown) for adjusting the stroke of the plunger. On the side opposite to the rack 33, the pinion 32 meshes with a similar rack 40 formed on a plunger 41, of smaller area than the plunger 34, working in a return cylinder 42 having an air connection 43.

The control means for the machine consists essentially of a cut-off valve 44, a control valve 45 for the ram cylinder 2 and a control valve 46 for the carrier-driving cylinder 35. The cut-off valve 44 (Fig. 5) comprises a piston 44¹ which is normally held, by air pressure from a connection 44², in the illustrated position in which open communication with a connection 44³ is maintained, but which can be moved by the operator to the cut-off position by means of a push rod 47 and cam 47¹ actuated by depression of a pedal 48. In the cut-off position of the valve, the connection 44³ is cut off from the connection 44² and connected to atmosphere through grooves 49 in the piston and exhaust ports 49¹. The valve 44 is preferably connected, by 44² and 44³ respectively, between the control valve 46 and the carrier-driving cylinder 35.

The ram-control valve 45 comprises a piston 50 working in a cylinder 51 with a supply port 52, ports 53 in communication through a connection 53¹ (Fig. 2) with the ram cylinder 2, and exhaust ports 54. In the outer position of the piston 50, the cylinder 2 is connected to supply and, in the inner position, to exhaust. The piston rod 55 engages a rod 56 connected to a bell-crank lever 57 and link 58 to a pedal lever 59, pivoted at 60, whereby the operator can move the valve piston 50 to the exhaust position. To assist the operator in so moving the piston 50, provision is made of a counter-balance cylinder 61 which is constantly under pressure through a connection 62 and whose piston 63 engages a rod 64 connected to an extension arm 65 of the lever 57. The arrangement is made such that there is a residual force tending always to move the valve piston 50 to the supply position. To ensure that the piston cannot so move except when one of the tables 8 is correctly located over the ram 4, a mechanical interlock is provided. This consists of a rocking lever 66 (Fig. 2) having one end pivotally connected to the rod 64 and the other end provided with a roller 67 which coacts with a flange 68 on the carrier hub 15 in such manner as to obstruct movement of the rod 64 and 75

the valve piston 50 towards the supply position. The flange 68 is provided, however, with slots 69 which come into register with the roller 67 when a table 8 is over the ram 4. The valve piston 50 can then move to the supply position, as the roller 67 is free to enter a slot 69.

The rod 56 is also connected (Figs. 1 and 3) through a link 70 to an arm 71 on the cam shaft 31, the arrangement being such that the cam 30 is operated to hold the clutch 23, 24 in engagement only while the valve piston 50 is in the exhaust position.

To allow of a compact and convenient arrangement of the operator's controls, the pedal 48 and cam 47¹ are pivoted on the pedal lever 59 and the push rod 47 is also guided thereon, as shown in Fig. 5. The arrangement is such that either control can be operated without affecting the other.

The valve 46 controlling the carrier-driving cylinder 35 has a permanently open supply port 72 (Fig. 3), exhaust ports 73 and a ring of ports 74 communicating through the connections 75, 44², 44³, 39 with the said cylinder 35. As far as port arrangement is concerned, this valve 46 may be a smaller version of the valve 45, communication between ports 74 and ports 72 and 73 respectively being controlled by a piston 76 which tends to be held in the supply position illustrated by the air pressure and is moved to the exhaust position only when the ram 4 rises to elevate a table 8. For this purpose, a roller 77 (Fig. 3) carried by a bracket 78 on the ram 4 is arranged to depress the piston 76 through its rod 79 by means of a bell-crank lever 80 pivoted at 81 in lugs 82 on the cylinder cover 5. The valve 46 is then held in the exhaust position until the ram 4 descends again.

The return cylinder 42 is not controlled by a separate valve, but is arranged to receive air from the ram cylinder 2 when the ram piston 3 has risen to its upper position. For this purpose the connection 43 is arranged to communicate with a port 84 (Fig. 3) so located in the wall of the cylinder 2 that it is open to the interior of the latter only when the piston 3 is in its upper position. When the piston 3 descends, it first cuts off the port 84 and then opens it to atmosphere or, preferably, allows exhaust by leakage past the piston above its piston packing 85.

For controlling and arresting the rotation of the table carrier 11, dash-pot braking means is arranged to act upon the driving system or the carrier, the dash-pot action being advantageously graduated or varied automatically during the travel of the carrier so as to permit of a required speed of rotation and deceleration. Preferably, the dash-pot action is exerted upon the plunger 34 of the carrier-driving system and for this purpose, in the arrangement illustrated in Fig. 4, a plunger 86 is arranged to work in a cylinder 87 mounted upon and coaxially with the cylinder 35. Oil-tight sealing means (not shown) is provided between the plunger 86 and cylinder 87. The cylinder communicates through passages 88, 89, controlled by adjustable needle valves 90, 91 with an oil reservoir 92 surmounted by a sight glass 93, the passages 88, 89 opening into the cylinder 87 at different distances from its end. The reservoir also communicates with the extreme end of the cylinder 87 through a passage 94 in which there is a non-return valve 95 which may be loaded by a spring (not shown). The plunger 86 is coupled to the plunger 34 in such manner as to permit of considerable lost motion between

them. To this end, the plunger 86 is provided with a head 96 (Fig. 2) which is received in a deep recess 97 in the plunger 34, the said head coacting, on the one hand, with the end 98 of the said recess and, on the other hand, with a shoulder-piece 99 attached to the end of the plunger 34.

The cycle of operations is briefly as follows: In the initial state of affairs, one table 8 is still being held in the elevated pressing position by the ram 4, while the other is accessible to the operator for placing an article thereon. The roller 67 of the interlock is in a slot 69 and the dog-clutch 23, 24 is disengaged. If, now, the operator depresses the pedal lever 59, the ram-control valve 45 connects the ram-cylinder 2 to exhaust, so that the ram 4 descends quickly and lowers the table 8 away from the head 6, at the same time connecting the return cylinder 42 to exhaust as hereinbefore described. The depression of the pedal 59 also withdraws the roller 67 from the slot 69 and causes the cam 30 to be turned to engage the clutch 23, 24. The descent of the ram permits the valve 46 to be moved by the air pressure so as to connect the carrier-driving cylinder 35 to supply. This stage of operation is illustrated in the drawings. The plunger 34 moves leftwards from the position shown in Figs. 2 and 4 and rotates the carrier 11 through 180° by means of the rack 33 and pinion 32, the engaged clutch 23, 24 and the gearing 19, 18, the return-cylinder plunger 41 being driven idly towards the right. In the initial part of this rotation, say for about one half thereof, the dash-pot 86, 87 exerts no control. When, however, the plunger 86 is entrained by the contact of the end 98 of the recess 97 with the plunger-head 96, a braking action commences to be exercised, such braking being initially moderate as both passages 88 and 89 are open. Towards the end of the carrier rotation, however, the passage 88 is cut off by the plunger 86 and the braking is thereafter harder. By adjusting the valves 90, 91, an appropriate graduated deceleration can readily be produced. Ultimately, the passage 89 is also cut off by the plunger 86 and the plungers 86 and 34 and the carrier 11 are brought to rest, the other table 8 being now over the ram 4. It is to be noted that the carrier is decelerated and arrested by the dash-pot means, not by the mechanical interlock. During the entire carrier rotation, the whole mechanical system connected to the ram-control valve 45 cannot return to its initial position, even after the operator has released the pedal 59, because the interlock roller 67 is riding upon the carrier flange 68 and thus holds the pedal depressed. However, when the carrier 11 has been arrested with the aforesaid other table 8 over the ram 4, the roller 67 is free to move into the other slot 69 and thus permit the pressure in the ram-control valve 45 to re-establish the initial conditions. Pressure is admitted to the ram-cylinder 2 and the ram 4 rises for a pressing operation. At the same time, the cam 30 is turned to allow the clutch 23, 24 to disengage. The rising ram 4 allows pressure to be communicated to the return cylinder 42 by way of the port 84 and moves the valve 46 to the exhaust position so that the plunger 34 can be returned idly to its initial position, through the racks 40 and 33 and pinion 32, by the plunger 41 of the return cylinder 42. In the latter part of the idle return movement of the plunger 34, it picks up the plunger 86 by means of the shoulder piece 99 and head 96 and draws the said plunger 86 back to the initial position shown in Fig. 2, oil 75

flowing back freely into the cylinder 87 past the non-return valve 95. The machine is now ready for the initiation of the next cycle whenever the operator wishes. Such next cycle is identical with that described above, the turning of the carrier 11 being always in the same direction.

Turning of the carrier 11 can be prevented or stopped at any point in the cycle of operations simply by depressing the pedal 43 (Fig. 5) to bring the plunger 44 of the cut-off valve 44 into the cut-off position. In normal operation of the machine, however, the operator has no need to close this valve.

We claim:

1. A garment press of the kind set forth, comprising in combination a press head, a horizontally rotatable carrier having two tables which can be brought in turn by rotation of the carrier into operative relation with the press head, fluid-pressure driven pressing means engageable sequentially with the tables, when in the said operative relation, for bringing them into pressing engagement with the press head, fluid-pressure operated means in driving connection with the carrier for turning it always in the same direction, a source of fluid pressure, fluid-pressure conduits extending between the source and the pressing means, and the source and the carrier turning means, a first valve in the conduit between the fluid-pressure source and the pressing means for controlling admission and discharge of pressure fluid to and from the pressing means, means for loading the valve towards the admission position for producing pressing engagement of the pressing means, operator-controlled valve-operating means connected to the valve for moving it to the discharge position for withdrawal of the pressing means from pressing engagement, means associated with the carrier-turning means and the said valve for holding the latter in the discharge position as long as neither of the tables is in the operative relation with the press head, a second valve in the conduit between the fluid-pressure source and the carrier-turning means for controlling admission of fluid pressure to the said carrier-turning means, and valve-operating means movable with the pressing means and engageable with the second valve for moving it to the admission position to admit pressure fluid to the carrier-turning means for producing rotation of the carrier when the pressing means is in the withdrawn position.

2. A garment press of the kind set forth, comprising a table carrier, pressing means, fluid-pressure operated means in driving relation with the said carrier for turning it always in the same direction of rotation, a source of fluid pressure, conduit means extending between said source and said pressing means and turning means, and fluid-pressure control apparatus connected in said conduit means between said source of fluid pressure and the said pressing means and the said carrier-turning means, including a single operator's control device, a valve system controlling the supply of pressure fluid to the pressing and carrier-turning means and initially operable by the said control device, the said valve system in its initial position being inoperative for causing movement of either the pressing or the carrier turning means, and restoring means acting upon the valve system for returning it automatically to the said inoperative initial position at the end of each pressing cycle, whereby operation of the said single control device causes a single cycle to be initiated and thereafter auto-

matically completed and the press brought to rest under the control of the control-apparatus without further intervention by the operator.

3. A garment press of the kind set forth, comprising two tables, a single pressing means, a horizontally rotatable carrier in which the tables are mounted and guided for vertical movement and by which they can be brought in alternation into operative relation with the pressing means, a source of fluid pressure, fluid-pressure operated means for turning the said carrier through 180° at a time always in the same direction of rotation, conduit means for supplying fluid pressure from said source to said turning means, a normally disengaged positive clutch device operatively connected between the fluid-pressure operated means and the carrier, and positively acting clutch-actuating means for producing engagement of the said clutch device for the turning of the carrier.

4. A press according to claim 3, comprising an operator's control-device connected to the pressing means for controlling the operation thereof, an operative connection between the control device and the clutch device for moving said clutch-device to positively engaging position upon actuation of the control device to effect release of the pressing means, and clutch-disengaging means in operative engagement with the carrier for automatically disengaging the clutch-device on completion of the turning movement of the carrier through 180°.

5. A press according to claim 3 and in which fluid-pressure operated means is provided for operating the pressure means, a conduit between said source and said pressing means, a valve in said conduit controlling the admission of pressure-fluid to the pressing means, means loading the said valve towards the admission position which produces pressing movement of the said means, an operator's control device, a connection between the said device and the said valve for moving the valve against the loading to the exhaust position for withdrawal of the pressing means, an operative connection between the valve and clutch device whereby the clutch device is caused to be engaged when the valve is moved to the exhaust position, holding means associated with the carrier whereby the clutch device is retained positively in the engaged position until the turning movement through 180° is completed, and loading means for returning the clutch device to the disengaged condition when no longer retained in the engaged position by the said holding means.

6. A press according to claim 1, wherein the second valve comprises a piston constantly urged towards the admission position by the fluid pressure, and a cylinder with ports in its cylindrical wall uncovered by the piston in the said admission position.

7. A press according to claim 1, wherein the carrier-turning means comprises a plunger working in a cylinder and a driving connection with the carrier including a rack and pinion and a releasable clutch device, means for returning the said plunger idly to its initial position, after it has turned the carrier, comprising a second plunger working in a return cylinder, a second rack connected to the said second plunger and meshing with the pinion, and pressure-fluid admission means connected to the return cylinder and controlled by the pressing means in such manner that return is effected only when the pressing movement has been produced.

8. A press according to claim 1 and an oil-filled dash-pot device for braking and arresting the turning movement of the carrier.

9. A press according to claim 4 and an oil-filled dash-pot device and including an arrangement of graduated oil passages for applying an automatically graduated braking action upon the said carrier during the later portion only of each turning movement of the carrier.

10. A press according to claim 1, wherein the carrier turning means comprises a driving plunger working in a cylinder and wherein a hydraulic dash-pot device is provided comprising a plunger coupled, with provision for relative lost motion, to the carrier-driving plunger and working in a horizontal cylinder which has two adjustably constricted connections from points, at different distances from its end, to a reservoir for hydraulic fluid.

11. A press according to claim 1, wherein the valve-operating means comprises a pedal and there is provided, in addition to the valve controlling admission to the pressing means, a cut-off valve in the fluid-pressure supply system, whereby the turning of the carrier can be arrested in any position, and operating means for the said cut-off valve connected to the said pedal.
